RACKET

John M. Le Compte and John B. Le Compte,
North Attleboro, Mass.

Application July 25, 1938, Serial No. 221,076

6 Claims. (Cl. 273—73)

This invention relates to a racket for various game uses; and has for one of its objects to provide a racket which will not warp due to moist conditions acting upon the strings of the racket.

5 A more specific object of the invention is to provide a means to prevent the inward movement of certain portions of the racket which initially occurs at the time warping takes place.

Another object of the invention is to strengthen 10 the head without unduly adding to the weight of the racket.

A further object of the invention is to provide a strengthening means which will leave the string portions of the contact area free for striking the ball uninterfered with by the strengthening portion.

15 A further and more specific object of the invention is to provide a part which will bridge the point to be prevented from inward movement 20 with the bridge supported from other parts of the frame.

With these and other objects in view, the invention consists of certain novel features of construction, as will be more fully described, and 25 particularly pointed out in the appended claims.

In the accompanying drawing:

Fig. 1 is a plan view of the racket with the handle broken off and illustrating the head as equipped with my invention;

30 Fig. 2 is a side elevation of the racket shown in Fig. 1;

Fig. 3 is a section on line 3—3 of Fig. 1;

Fig. 4 is a section on line 4—4 of Fig. 1;

35 Fig. 5 is a plan view of the complete racket with a modified form of strengthening means;

Fig. 6 is an enlarged sectional view showing in detail the tightening means for the strengthening strand;

40 Fig. 7 is a fragmental sectional view showing the securing of the strengthening strand.

In rackets, especially the more expensive rackets, the strings of the racket are placed in the head frame very tight. These strings are of lamb's gut which are hydroscopic and when moist shrink to such an extent as to cause tremendous strains to be exerted upon the frame of the racket. In studying the conditions of warping, it is found that the top of the frame first moves inwardly as warping commences and thereafter 45 the sides of the frame move inwardly in a similar manner. Accordingly, in order to prevent warping we intend to strengthen the top and the sides of the frame where the frame is of thin or lighter construction by providing a means to prevent 50 this inward movement of the frame at these

points; and the following is a more detailed description of the present embodiment of this invention, illustrating the preferred means by which these advantageous results may be accomplished:

With reference to the drawing, 10 designates the head or frame of the racket of a generally elliptical shape which is usually formed by a bent strip of wood either of several pieces or a single piece forming a top portion 11, side portions 12, 12', while the ends of this strip of wood extend down into the handle 13 usually with some insert at the throat portion 14 and some covering of a layer of wood or the like to provide the handle 13. There also is usually some 15 strengthening covering at 15 which extends up the sides of the frame a short distance. The weakest portion of a frame so constructed is at the top portion 16, while other weak portions of the frame are as at 17, 17' on the sides. These 20 weak portions cannot very well be strengthened by thickening the material without adding excessive weight to the racket which cannot be balanced in the handle, and accordingly expensive rackets with strings which are strung tight are 25 put into a press almost immediately upon completion of use so as to prevent a warping or twisting of the head frame 10 in which the strings 18 are placed in a usual manner.

In order to prevent the portions 16 or 17 from 30 moving inwardly by reason of the tension on the strings 18, we have provided a strand 20 which extends across the arcuate top 21 of the frame and through openings 22 in the head frame 10 and thence along the outer surface or in a groove 35 in the outer surface as at 23, 23' and again inwardly through openings 24, thence across the acuate portion 25 as at 26, 26' and again through openings 27, 27' and along the outer surface or in the groove 28 of the portion 29 of the frame. 40 Thence again inwardly as at 30, 30' and across the lower part of the frame and through the frame again as at 31, 31' where they are suitably anchored by tucking back into the frame and being knotted, see Fig. 7, or in any suitable manner.

The head frame consists of a main portion above described and an auxiliary portion which will presently appear. The portions 20, 26 and 50 26' of the strand or member which extends along the inner surface of the frame engage the inner surface of the frame so as to provide a support against inward movement for the portion of the frame along the inner surface of which the strand extends. In order to provide this support the en- 55

gagement of the frame with the strand should occur along the strand at a plurality of points or substantially throughout the extent of the strand along the inner side of the frame. Where the 5 material of the main frame is bent into the shape shown, it is desirable that the frame be of a substantially uniform thickness, and accordingly, when this portion of the frame is so formed, it is concavely arcuate along its inner surface. Thus, 10 in order that the frame may contact the strand at the middle and at other points of its extent over the inner surface, we build up or supply an auxiliary portion of the frame at the location between the holes 22, 24, 27, 24', 27' by additional 15 portions 32, 33, and 33' to increase the dimension of the frame in order that the frame may be braced at these locations. These additional parts of the frame may be considered as struts or braces. Another form of causing the frame to be 20 supported is by providing recesses 40 adjacent holes or openings 22, 24, 27, 24', 27' on the inner surface as shown in Fig. 5 so that the strand may contact the frame from the inside at its middle and other points along its extent. As this strand 25 is exceedingly tight and any movement at the top 16 would pull upon the side portions 23, 23' of the strand in affording inward movement, and since this cannot move inwardly because of the tight condition and the support from the outer 30 surface of the frame, we effectively prevent the top 16 or the sides 17 and 17' from inward movement so that this movement cannot occur; and we have found that a racket braced in this manner will withstand strains which will warp the 35 usual racket not so supported.

The strand 20 may be of the same gut material that is used for the stringing of the racket or it may be wire, and when we provide a wire which we will designate 35 in Figs. 5 and 6, we will provide 40 a bore 37 in the head 10, thread the ends of the wire 35 as at 38 and provide a nut 39 which will abut the bottom of the bore and when turned will tighten up the wire 35 to provide a tightening device for providing a firm support for the 45 bridging part of the wires which pass within the head frame.

The portions such as 32 and 33 which we provide 50 need not be such as to completely fill the space between the support strand and the outer portion of the frame as any means resting against the strand and preventing movement of the outer portion of the frame inwardly will provide a desired function.

By reason of the stringing device extending peripherally about the frame the strings are left 55 free during the entire playing area and the weight which is added to the frame may be readily compensated for in the handle, it being at the most not more than a fraction of an ounce.

60 The foregoing description is directed solely towards the construction illustrated, but we desire it to be understood that we reserve the privilege of resorting to all the mechanical changes to which the device is susceptible, the invention being 65 defined and limited only by the terms of the appended claims.

We claim:

1. In a racket, a head frame carrying a plurality of strings, a member extending along the outer surface of the frame for a portion of its extent and then passing through the frame and extending along and in contact with the inner surface of a portion of the frame for providing a support to prevent inward movement of the frame along said portion. 5

2. In a racket, a head frame, a member extending lengthwise circumferentially along the outer surface of the frame for a portion of its extent and then passing through the frame and extending generally lengthwise circumferentially along the inner surface of the frame in contact therewith for a portion of its extent and providing a support to prevent inward movement of the frame along said portion. 10 15

3. In a racket, a head frame carrying a plurality of strings, a member extending along the outer surface of the frame for a portion of its extent and then passing through the frame and extending along and in contact with the inner surface of a portion of the frame, said frame being increased in its dimension to engage the member extending over its inner surface. 20 25

4. In a racket, a head frame carrying a plurality of strings, a member extending along the outer surface of the frame for a portion of its extent and then passing through the frame and extending along and in contact with the inner surface of a portion of the frame for providing a support to prevent inward movement of the frame along said portion, the extent of the member along the inner surface of the frame occurring at the top of the head and at each side portion thereof. 30 35

5. In a racket, a main frame, a member extending along the outer surface of the main frame for a portion of its extent and then passing through the frame and extending along the inner surface of the main frame and in spaced relation to a portion of the main frame for a portion of its extent, and an auxiliary frame portion 40 45 engaging the member and inner surface of the said portion of the main frame to hold the frame against inward movement. 50

6. In a racket, a frame, a strand having portions extending along the length of the outer surface of the frame and disposed at spaced portions of its extent, and other portions of said strand passing through the frame and extending along the inner surface of the frame at the top and sides thereof and in spaced relation for a portion of its extent to bridge said inner surface, and means engaging the bridging portions of said strand and said inner surface of the frame to provide supports to hold the top and sides of said frame against inward movement, owing to any tendency of said frame to deformation under tension of the vertical and transverse strings with which the frame usually is strung. 55 60 65
